A. & G. M. FOSTER.
MACHINE FOR PRESSING AND MOLDING HOLLOW BRICK.
No. 15,374. Patented July 22, 1856.

UNITED STATES PATENT OFFICE.

AMBROSE FOSTER, OF NEW YORK, N. Y., AND GEORGE M. FOSTER, OF FAIRHAVEN, CONNECTICUT.

MACHINE FOR MOLDING AND PRESSING BUILDING-BLOCKS FROM CLAY, &c.

Specification of Letters Patent No. 15,374, dated July 22, 1856.

To all whom it may concern:

Be it known that we, AMBROSE FOSTER, of the city, county, and State of New York, and G. M. FOSTER, of Fairhaven, in the 5 county of New Haven and State of Connecticut, have invented a new and useful Improvement in Machinery for Molding and Pressing Building Material; and we do hereby declare that the following is a full, 10 clear, and exact description of the same, reference being had to the annexed drawings, making a part of this specification, in which—

Figure 1, is a vertical section of our improvement, (x), (x), Fig. 2, showing the 15 plane of section. Fig. 2, is an end view of the same.

Similar letters of reference indicate corresponding parts in the two figures. 20 Our invention consists in the employment or use of a sliding hopper, plunger, and vibrating press box, arranged and operated, as will be hereinafter fully shown and described.

25 To enable those skilled in the art to fully understand and construct our invention, we will proceed to describe it.

A, A, represent two uprights which are attached to a suitable base B, and C, represents the driving shaft of the machine, said shaft working in suitable bearings at the upper parts of the uprights A, A. On one end of the shaft C, there is placed a driving pulley D, and a pinion E, is placed 35 on the opposite end of said shaft. The pinion E, gears into a toothed wheel F, which is placed on one end of a shaft G, which works in bearings at the lower parts of the uprights A, A. On the shaft G, there is 40 placed a cam H, which works between the two uprights A, A. The form of this cam is distinctly shown in Fig. 1, a portion (a), of the cam is a segment of a circle, and a portion (b), is a segment of a smaller circle, 45 and a portion c is a segment of a still smaller circle. One side (d), of the larger segment (a), is placed tangentially with the segment (b), while the opposite, (e), is of curved form, see Fig. 1.

50 I, represents a plunger, which is fitted and works in a press box J. This press box is fitted between the upper parts of the uprights A, A, and rests upon screw heads (f). The press box has vertical grooves or

55 recesses made in its ends, in which the inner

sides of the uprights fit, and a certain degree of vertical play or vibration is allowed the press box, as will be hereafter shown. The plunger I, is attached to the upper ends of two sliding bars (g), which are fitted in 60 boxes (h), at the inner sides of the uprights A, A, and a friction roller J', is attached to the lower ends of the sliding bars, said roller bearing upon the cam H.

The interior of the press box in which the plunger works is of rectangular form, and has a core K, fitted vertically within it, the core passing through the center of the plunger, its upper end being flush with the upper surface of the press box, as shown in 70 Fig. 1. The upper end of the press box J, has a horizontal plate L, attached to it, on which plate a sliding hopper M, works, said hopper having guides (i), (i), attached to it, one at each side, which guides work in 75 recesses or grooves in the upper ends of the uprights A, A.

On the inner side of the toothed wheel F, there is a cam formed of two irregular shaped ledges (j), (j'), between which a pin 80 (k), works, said pin being attached to an upright lever N, the lower end of which is attached to a shaft O. The upper end of the lever N, is attached by a pitman P, to the hopper M. On the inner side of the 85 wheel F, there is also a segment ledge (l) which acts against the lower end of a lever Q. This lever Q, works on a fulcrum at (m), and is of bent or right angular form, the upper horizontal portion of the lever being attached to the press box J, by having the end of the lever fit in an eye (n), on the box.

To the under surface of the plunger I, there is attached a curved or bent arm R, 95 which has a hook or lip (n) upon it, near its lower end, see fig. 1. The lever end of the arm R, bears against the upper end of a curved arm S, attached to the base B, and the segment portion (a), of the cam H, is 100 slotted, so that the arm may pass into it, as the cam rotates, the segment portion (a) has also a recess (o), cut in it, into which the hook or lip (n), falls, as said recess passes around opposite to the lip or hook.

T, is a set screw, which passes vertically through the lower end of the press box J, this set screw controls or governs the length of stroke of the plunger I.

The operation is as follows. The cam H 110

operates the plunger I, the cam formed of the ledges (j), (j), on the wheel F, operate the sliding hopper M, and the ledge (l) operates the press box J. The material is placed within the hopper M, when in the position shown in blue, and designated by Fig. 1, see Fig. 1, and as the driving shaft C, is rotated, the hopper M, is moved forward by the ledges (j), (j'), and lever N, to a point directly over the press box J, as shown by the Fig. 2, and the material falls into the press box, the plunger I, being depressed or at the lower end of the press box, and the friction roller J', being upon the small segment (c), of the cam H. The hopper then moves back in the position shown in red, and indicated by the Fig. 3, and a cross plate V, at the front side of the hopper is directly over the press box. The plunger I, is now forced upward by the segment portion b, of the cam H, and the material is compressed within the press box. Just previous however to the rising of the plunger I, the ledge (l), will strike against the lower end of the lever Q, and the press box J, and plate L, will be forced upward firmly against the cross plate V, and retained in that position, until the material within the press box is compressed, the press box then falling down to its original position. The hopper M, now moves back to its original position, as shown in blue, and designated by the Fig. 1, and the segment portion (a), of the cam H, forces the plunger up to the top of the press box, and the molded and compressed material is forced from the press box, and

removed from off the plate L, when the hopper M, is again moved forward over the press box.

The above machine has been practically tested, and operates smoothly and well. There are no parts liable to get out of repair, nor become injured or worn in case of wear, as the working parts are all protected. The arm R, is employed to draw down the plunger, in case it sticks within the press box. This is effected in consequence of the hook or lip (n), catching into the recess (o), in the segment (a), of the cam H.

We do not claim a sliding hopper nor do we claim a core placed within a press box for the purpose of molding hollow brick, for these devices have been previously used; but

Having thus described our invention, what we claim as new, and desire to secure by Letters Patent, is—

1. The sliding hopper, M, plunger, I, and vibrating press box, J, when the above parts are moved or operated relatively with each other, as shown, for the purpose specified. 60

2. We claim operating the hopper, M, press box, J, and plunger, I, by means of the cam, H, on the shaft, G, the ledges, (j), (j'), and (l), on the wheel, F, and levers, N, Q, the above parts being constructed and arranged substantially as shown and described. 65

AMBROSE FOSTER.
GEORGE M. FOSTER.
